SEPARABLE GARMENT AND SLEEPING BAG
COMBINATIONKarl Manheim, Eyn Ayala, near Haifa, and
Paul Gamsz, Naharia, Israel

Application May 15, 1951, Serial No. 226,364

1 Claim. (Cl. 2-70)

1

The present invention relates to a garment destined to serve a variety of purposes. The garment is intended in the first line for military use, and for this reason the following description deals mainly with such use and with advantages connected therewith.

The upper clothes worn by soldiers and/or carried with them are usually—besides a pair of trousers—a blouse, a greatcoat, a raincoat or cape and two blankets. In lieu of a raincoat the soldier may have a waterproof groundsheet.

The present invention provides a garment serving all the purposes to which in usual use the above garments are put.

The new garment according to the invention is composed of an upper and a lower part, the upper part being in the nature of a military blouse and the lower one being skirtlike, both parts being joined together at approximately the waist line, preferably by buttons, and, when so united, forming a greatcoat. If separated the two parts can be used independently from each other as will be set out. The blouse is provided with a waistband to be tightened more or less and fixed in such position so as to give the blouse a proper fit. A similar band is preferably provided in the lower part at its upper edge for a purpose to be described.

In a preferred embodiment of the invention the sleeves are detachably fastened to the upper part of the garment. These and other features of the invention will become clear from the following detailed description in connection with the drawings in which:

Fig. 1 is a frontal view of the garment completely assembled to serve as a greatcoat;

Fig. 2 shows the upper part, serving as a blouse, with one sleeve detached;

Fig. 3 shows a separate saddle part to be worn on the shoulders while

Fig. 4 shows the lower part laid flat.

Turning first to Fig. 1, wherein the new garment is shown in its assembled form, we see the upper jacket-like part A, the lower skirt-like part B and the saddle part C.

The upper part, as seen in Fig. 2 has the conventional buttons 1 and buttonholes 2 of a double breasted coat or jacket.

Additional buttons 3 are provided on the front (and corresponding buttons at the back, not seen in the drawing) for buttoning the saddle C to the jacket. Along the edge of the arm holes, small holes 4 are provided registering with similar holes 5 in the upper edge of the sleeve 6. Preferably these holes 4, 5 are punched in leather strips sewn

2

to the respective edges of part A and the sleeves 6. A string or cord is passed through these holes, thus securely fitting the sleeves to the jacket, but allowing for a detachment of the sleeves from the garment, whenever this is desired. Those skilled in the art know that sleeves can be fixed in a garment either "normally," i. e. in a "hanging down" position or raised, say through 10 or 15 degrees of an angle. The latter position is required for persons who have to raise their arms most of the time to perform some operation, e. g. dispatch riders, coachmen, hunters, etc. This position gives greater freedom to the arms, insofar as a heavy coat does not hamper the movement of the arms. Thus the holes 4, 5 being at equal distances from each other, the sleeves may be attached to the garment in one or the other position. A proper mark is provided to indicate one or both positions.

20 A sheath 7 is provided at about the waistline on the inside of the garment and a band is drawn therethrough. This allows for giving a tight fit to the jacket A.

Part B is attached to part A by buttons 8 sewn 25 around the jacket A somewhat below the waistline.

Part B is made of two plies. Buttonholes 8' are provided in the inner ply corresponding to buttons 8.

30 Part B is seen in Fig. 4. The two plies are sewn together along three sides at 9, while at the fourth side a slide fastener 10 is provided. One of the plies is preferably of rubberized material or waterproof canvas. Along edge 11 a sheath is provided through which is drawn a band. This allows for using part B as a short cape, tightening the band in sheath 11 around a person's neck.

35 The saddle-part C shown in Fig. 3 is also made of two plies. A portion of it C' (worn on the back of the person) is made from airtight material, and can be inflated.

40 The use of the garment is obvious:

1. A greatcoat is formed by parts A and B when assembled, with or without part C.
2. Part A may be worn as a jacket with sleeves, or
3. As a sleeveless garment.
4. Part B when detached from A serves as a sleeping bag, by opening zipper 10. It may be used even on moist ground, since one of the plies is watertight.
5. Part B serves as a cape with the band in sheath 11 drawn tight.
6. Part C is worn on the coat or jacket as a

protection against rain, and if inflated it is used—
7. As a cushion.

A hood or cowl can be provided and buttoned to part A in a conventional manner, or to part B, when worn as a cape.

The bag formed by part B serves as a receptacle for the parts not actually used.

It will be seen that with the new garment the soldier has to carry about 40% only of the weight he has to carry in using conventional uniform parts. The economy in fabric is obvious. Blankets are no more used at all. Of course the new garment can be made in any style desired, with pockets, buttons etc. according to regulations or requirements. A belt will preferably be worn covering the joint between parts A and B.

What we claim is:

In a man's garment, an upper jacket-like part and a lower skirt-like part detachable therefrom, the latter part being composed of two plain four-edged plies the inner ply of which is a water-proof material and the two plies being sewn together at three edges thus constituting in the detached state a flat bag, the sewn two plain plies having the configuration of a trapezoid, a 25

for securing said plies together along said edge, the short edge of the trapezoid being provided with both buttonholes for attaching that lower part to the upper part and with a sheath through which a band can be drawn for tightening that lower part around the waist line of the user.
